SPRING PROTECTOR

Arthur M. Ferrin, Eden, Utah

Application March 9, 1936, Serial No. 67,754

4 Claims. (Cl. 16—72)

My invention relates to springs and has for its object to provide a new and efficient protector for screen door springs.

A further object is to provide a spring metal guard for coil springs which guard has each end engaged with the spring and is adapted to bend with the spring to protect the spring and keep it from breaking where it bends around a sharp angle.

10 A still further object is to provide a door and spring protector which will protect both the spring from breaking or excessive stretching where it engages the corner of the door, and which will also protect the corner of the door 15 from being marred by the bending of the spring therearound.

These objects I accomplish with the device illustrated in the accompanying drawing in which similar numerals and letters of reference indicate like parts throughout the several views and 20 as described in the specification forming a part of this application and pointed out in the appended claims.

In the drawing in which I have shown my device and its uses,

25 Figure 1 is a plan view of the device shown attached to the door jam and to the door, parts cut away.

Figure 2 is a side elevation of Figure 1.

30 Figure 3 is a plan view of the spring protector.

Figure 4 is a face view of Figure 3.

Figure 5 is an end view of the one end of the 35 guard or protector which engages the end of the spring.

Figure 6 is an end view of the end of the protector which engages around the spring.

Figure 7 is a plan view of the device showing the door opened.

40 Figure 8 is a view of a section of the spring showing a cylindrical slide in the end of the spring guard.

In the drawing I have shown the door jam as A, and the door as B. The hinge is shown as C and suitable hooks or attaching devices are shown 45 as D in the door jam and E in the door.

Into the door jam the hook D is screwed and the hook E is screwed into the door a proper distance to give the correct amount of tension to the spring S.

50 The spring S is of the usual variety for closing screen door or like closures and the ends of the spring are provided with loops 5 and 6, one loop 5 to engage the screw hook D and the other hook 6 to engage the hook E.

55 Onto the spring S I then secure my spring metal guard or protector which consists of a flat strip of spring metal 10 having one end 11 bent out from the body on an angle and having

a round hole 12 therethrough, the end 11 to encircle the spring. The other end 13 of the metal strip 10 is bent out at an angle and has preferably a square hole or rectangular hole 14 therethrough. This hole is to be attached over 5 the loop 5 to hold the end of the metal strip 10 in proper position at all times for protecting the spring and for protecting the door.

The end 11 of the strip 10 may be provided with a cylindrical socket 16 to slide over the 10 spring as shown in Fig. 8, so that the end of the strip 10 will never get caught in the coils of the spring S.

Figure 7 shows the use of the spring guard to hold the spring from engaging against and mar- 15 ring the corner 17 of the door and to prevent spreading of the coils of the spring S thereby weakening the spring and stretching its coils so that they do not have any tension to draw the door closed.

This device may be used on and with any 20 spring where it is to be flexed around or against an angled surface to protect the spring and also the surface and any deviation or departure from the showing as set out in the drawing and such 25 improvements as may be made do not depart from the spirit of the invention nor from the scope of the claims.

Having thus described my invention I desire 30 to secure by Letters Patent and claim:

1. In a spring for doors, the combination of a 35 coil spring; means to secure the ends of the spring, one end to the door jam and the other end to the door; a flat door and spring guard carried on said spring with one end secured to the end of the spring which is secured to the door jam and the other end slidably carried on said spring.

2. In a closure spring to hold a closure in normally closed position, the combination of a coil 40 spring mounted on the closure and on the frame in which it is suspended; and a flat metal spring carried with the flat side to engage the closure when it is opened, said spring to bend around the edge of the closure when it is opened with 45 the curve of the coil spring.

3. In a closure spring, the combination of a coil spring; a flat metal guard for said coil spring mounted with one end to move on the exterior of said spring and the other end to be secured 50 to the end of the coil spring where it is secured to the frame in which the closure is to operate.

4. A spring guard comprising, a flat strip of metal having the ends bent out at an angle to the body one end to be secured to the spring and 55 the other end to be slidably carried on said spring, the entire guard to bend with said spring.

ARTHUR M. FERRIN.
